Primary Examiner — Karen E Eldridge Powers(74) *Attorney, Agent, or Firm* — Maier & Maier, PLLC(57) **CLAIM**

The ornamental design for a support pocket for men's underwear, as shown and described.

DESCRIPTION

FIG. 1 is a front elevational view of a support pocket for men's underwear, showing my design;

FIG. 2 is a front elevational view thereof, showing the front flap unfastened;

FIG. 3 is a rear elevational view thereof, it being understood that the rear view is seen from the interior of the underwear; and,

FIG. 4 is a cross-sectional view thereof, along line A-A of FIG. 1.

The 'dash-dash-dash' broken lines shown throughout the drawings represents conventional stitching.

The 'dot-dot-dash' broken lines shown throughout the drawings illustrate the article to which the design is applied and form no part of the claim.
